ERNEST DRINGMAN, OF PAXTON, NEBRASKA.

SAND-GUARD FOR IRRIGATION-DITCHES.

1,348,554.

Specification of Letters Patent. Patented Aug. 3, 1920.

Application filed May 3, 1917. Serial No. 166,195.

To all whom it may concern:

Be it known that I, ERNEST DRINGMAN, a citizen of the United States, residing at Paxton, in the county of Keith and State of Nebraska, have invented a new and useful Sand-Guard for Irrigation-Ditches, of which the following is a specification.

This invention relates to sand guards for irrigation ditches.

10 The object of the invention is to provide a construction which will prevent sand from drifting or being washed into the ditch from the river or other source of water supply with which the ditch communicates, and also 15 will avoid the accumulation of sand in front of the head gate for the ditch, whereby a free and full flow of water through the ditch during the irrigation period or season is obtained.

20 In the accompanying drawing I have illustrated one embodiment of my invention, in which:

Figure 1 is a longitudinal section taken through the river or stream immediately in 25 front of the head gate on the line 1—1 of Fig. 2.

Fig. 2 is a transverse sectional view across the stream on the line 2—2 of Fig. 1, looking in the direction of the arrow.

30 Fig. 3 is a perspective view of the structure embodying the invention.

In irrigation systems, a river or stream 1 furnishes water for a ditch 2 which communicates therewith and is arranged at an 35 angle relatively thereto. At the point where the ditch communicates with the stream or river, a head gate 3 having check boards 4 arranged therein in the usual manner to control the quantity of water entering the ditch, and a floor 5 arranged substantially in alinement with the bottom 5^a of the stream or river is provided.

40 Along the bank of the river, both above and below the head gate 3 and beneath the head gate, is placed sheet piling 6 for preventing the current from tearing away the dirt around the head gate, and for the purpose of providing a foundation for the head gate itself.

45 As shown in Fig. 2, a vertical wall 7 projects downwardly below the floor 5 and is buried in the bed 8 of the river and extends from one end of the head gate to the other. The upper stratum of the bed 8 comprises

loose sand and water which is easily 55 washed into the ditch and which it is my purpose to keep out. For attaining this result, a shelf or platform constituting a sand guard 10 is fixed to the wall 7 in front of the head gate and projects outwardly toward 60 the center of the river or stream. At the upstream end 11 of the head gate, the guard 10 is substantially at the same level with the floor 5 of the head gate and with the bottom 5^a of the river or stream. From 65 this point the guard 10 inclines downwardly toward the down-stream end 12 of the head gate, and is arranged somewhat below the floor 5 of the head gate and bottom 5^a of the river at the lower end thereof. It 70 should be noticed that the guard 10 is arranged in front of the head gate and extends from one end thereof to the other and is buried in the bed of the stream at its lower end.

75 Arranged below the guard 10 and spaced therefrom is a horizontally extending apron 13, which is buried within the bed 8 of the river several feet below the bottom 5^a thereof. The apron 13 also extends the full 80 length of the head gate and is arranged substantially parallel with the floor thereof. The guard 10 and apron 13 provide therebetween a channel 14 restricted at its lower end through which the loose sand and 85 water, which forms the upper stratum of the bed, drifts or is directed. The sand guard prevents the sand from drifting through the head gate into the ditch and also directs it away from the gate at the 90 lower end thereof and in a direction downstream.

Extending transversely of the stream at the down-stream end of the head gate is 95 the usual dam or weir 15, which is supported by a row of sheet piling 16 extending transversely of the stream and embedded in the bottom thereof. As shown in Fig. 2, the weir is provided at its upper portions with check boards 17 to regulate the flow of 100 water therethrough. The portion 18 of the weir adjacent the lower end of the sand guard is built into the bed of the river, and is provided with a base or floor 20 extending substantially transversely of the stream and in alinement or at the same level with the apron 13, as shown in Fig. 1. As shown in Fig. 2, the portion of the weir remote

- from the head gate and sand guard is provided with a floor or base 20^a which rests directly upon the bottom of the stream and at a higher level than the floor or base 20.
- 5 The framework of the portion 18 of the weir, however, provides a passage 21 through which the drifting sand escapes when directed by the apron and sand guard, as clearly shown in Fig. 1. For this purpose, 10 it should be noticed that the check boards 17 of the portion 18 of the weir are located entirely above the sand guard, so that the sand within the channel 14 has an open avenue of escape with the current.
- 15 From an inspection of Fig. 2, it will be seen that the apron 13 is considerably wider than the sand guard and projects farther into the stream. Both the apron and sand guard, however, extend from one end of 20 the head gate to the other, while the sand guard inclines downwardly toward the down-stream end thereof and toward the apron. The channel 14 which is restricted at the down-stream end thereof causes the 25 current to carry the sand away from the front of the head gate, and through the passage 21 of the weir, so that no deposits of sand will form in front of the head gate or drift into the ditch, filling up the same 30 and preventing the free flow of water therein.

The action of the dam or weir 15 is to divert a portion of the water flowing down-stream into the ditch or lateral 2, and this 35 diverted part of the stream would, if provision were not made to prevent it, carry more or less sand into the lateral 2, since there is a tendency to an upflow of the water, carrying sand with it, into the lateral. The sand guard, however, prevents this, since it extends the full length of the 40 head gate and is over the apron 13, so that a current is produced between the sand guard and the apron discharging through 45 the opening at the downstream end of the channel 14. Because of the lesser height of the downstream end of the channel 14, there is a tendency to accelerate the flow, and the mobile water-charged sand is carried 50 through the opening in the weir, while any sand which may reach the top of the sand guard is carried through the opening 21.

Even if the depth of the sand is considerably less than that indicated in Figs. 1 55 and 2, there would still be a tendency of producing an uplift or suction on the sand by the water flowing through the head gate into the lateral, which suction is entirely obviated or counteracted by the sand guard 60 10, so that the lateral is kept free from sand.

While I have shown and described one embodiment of my invention, it is to be understood that I do not desire to be limited 65 to the details of construction herein shown

and described, for obvious modifications will be apparent to anyone skilled in the art.

What is claimed is:—

1. The combination with the head gate of an irrigation ditch, of a sand guard consisting of an inclined shelf or platform arranged in front of the head gate and extending from one end thereof to the other, said guard having its high end up stream and arranged substantially on the level with the 75 floor or bottom of the head gate.

2. The combination with a head gate controlling the water supply from a stream to a ditch, of a sand guard extending lengthwise of the stream and arranged in front of the 80 head gate at the bottom thereof and projecting from said head gate toward the middle of the stream.

3. The combination with a head gate for an irrigation ditch, of a guard fixed to said 85 head gate and projecting into a supply stream, said guard being arranged at the up-stream end thereof substantially at the same level as the bottom of the ditch and at the down-stream end thereof lower than 90 the bottom of the ditch.

4. The combination with a head gate controlling the water supply from a stream to a ditch, of a guard arranged in front of said head gate at the bottom of the latter and 95 projecting toward the middle of the stream, and an apron spaced below said guard.

5. The combination with a head gate having a floor and separating a ditch from a supply stream, of a guard projecting from 100 said head gate into the stream and arranged at the up-stream end thereof in substantial alinement with the floor and bottom of the ditch and at the down-stream end thereof below the level of the floor and an apron 105 spaced below said guard.

6. The combination with a head gate controlling the water supply from a stream to a ditch, of a guard projecting toward the middle of the stream and fixed to the front 110 of the head gate at the lower portion thereof, and an apron spaced below said guard, said guard and apron converging toward each other at their down-stream ends.

7. The combination with a head gate 115 controlling the water supply from a stream to a ditch, of a guard projecting from said head gate into the stream and arranged at the up-stream end thereof in substantial alinement with the bottom of the head gate and 120 ditch and at the downstream end thereof below the bottom of the ditch, an apron spaced below said guard, and projecting outwardly from the front of said head gate, said guard and apron converging toward 125 each other at their down-stream ends and extending from one end of said head gate to the other, and a weir extending transversely of the stream below the head gate and provided with an unobstructed passage 130

therethrough below and adjacent to the down-stream ends of the guard and apron, whereby drifting sand is directed through the passage away from the head gate by 5 the guard and apron.

8. The combination with a head gate controlling the water supply from a stream to a ditch, of a guard projecting toward the middle of the stream and fixed to the front 10 of the head gate at the lower portion thereof, an apron spaced below said guard and of a width greater than said guard, said apron and guard converging toward each other at their down-stream ends, and a weir 15 extending transversely of the stream and below the head gate and provided with an unobstructed passage therethrough below and adjacent to the down-stream ends of the guard and apron, whereby drifting sand is

directed through the passage away from the 20 head gate by the guard and apron.

9. The combination with a head gate controlling the water supply from a stream to a ditch, of a sandguard arranged longitudinally in the stream in front of the head gate 25 at the bottom thereof and projecting toward the middle of the stream, and an apron spaced below and of a width greater than said guard, the apron and guard converging toward each other at their down stream 30 ends.

In testimony that I claim the foregoing as my own, I have hereto affixed my signature in the presence of two witnesses.

ERNEST DRINGMAN.
